United States Patent Office

Des. 204,021
Patented Mar. 8, 1966

204,021

HOLDER FOR SPECTACLES OR THE LIKE

Rosa Cira del Carmen Fierro de Bachmann,
Uruguay 1133, Buenos Aires, Argentina

Filed Oct. 14, 1963, Ser. No. 76,956

Term of patent 14 years

(Cl. D57—1)

FIG. 1 is a perspective view of a holder for spectacles or the like, embodying my new design;

FIG. 2 is a top plan view;

FIG. 3 is a sectional view taken on the line 3—3 of FIG. 1; and

FIG. 4 is a front elevational view.

I claim:

The ornamental design for a holder for spectacles or the like, as shown.
